UNITED STATES PATENT OFFICE.

HALVER R. STRAIGHT, OF ADEL, IOWA.

BUILDING-BLOCK.

1,191,363.

Specification of Letters Patent. Patented July 18, 1916.

Application filed October 7, 1912. Serial No. 724,448.

To all whom it may concern:

Be it known that I, HALVER R. STRAIGHT, a citizen of the United States, residing at Adel, in the county of Dallas and State of Iowa, have made certain Improvements in Building-Blocks, of which the following is a specification.

The object of my invention is to provide a building block especially adapted to be 10 constructed of vitrified clay, and especially designed for use in the construction of the walls of circular buildings such as silos, and to provide a building block of this 15 class that may be manufactured by the use of ordinary tile making machinery provided with a die of suitable shape.

More specifically it is my object to provide a building block of this class in which 20 a binding wire or rod may be readily and easily placed in position, and there temporarily held while the mortar is being applied, and after the mortar is applied and the building block placed in position on the 25 top of it, the exposed portion of the mortar will be relatively small and yet the thickness of the layer of mortar surrounding the binding rod or wire will be relatively great, thus providing a layer of mortar that, from 30 the center of the layer to the inner face of the wall will be wedge-shaped so that when strains are applied to the wall outwardly, the wire or rod cannot cut or shear through the mortar but would have to first crush the wedge-shaped portion of mortar before the 35 wall could spread or incline outwardly, thus obtaining a considerable advantage in regard to the strength of the wall on account of the fact that the crushing strength of mortar or cement is many times greater than 40 its strength is opposed to cutting or shearing strains such as would be applied to the mortar by the wire or rod when pressure is applied outwardly to the wall.

A further object is to provide a block of 45 this kind that can be readily and easily handled, and that will readily stand in an upright position when placed on a horizontal support with either of its narrow edges 50 undermost for convenience in handling the blocks.

My invention consists in the construction of my improved building block whereby the objects contemplated are attained, as hereinafter more fully set forth, pointed out in my claims and illustrated in the accompanying drawings, in which—

Figure 1 shows a vertical, transverse, sectional view through two building blocks embodying my invention and laid together with a layer of mortar between them as in 60 use, and Fig. 2 shows a perspective view of a portion of a circular wall constructed of my improved building blocks.

Referring to the accompanying drawings I have used the reference numeral 10 to 65 indicate the side walls of the building block and 11, the horizontal, transverse partition. These parts are plain and straight and are of ordinary construction. The top member of my improved building block comprises a 70 body portion 12 which is curved downwardly at its central portion. The top surface of the part 12 is inclined downwardly and inwardly at 13 toward the longitudinal center and at a point spaced laterally from 75 the longitudinal center is a vertical shoulder 14, the central portions 15 between the vertical shoulders 14 being straight.

The lower part of my improved building block comprises a body portion 16 which is 80 straight and arranged at right angles to the side members 10 and this lower edge has its side portions inclined inwardly toward the longitudinal center of the block and slightly downwardly at 17, the incline of the 85 part 17 being less than the incline of the part 13, so that when these two parts are placed together, as shown in the upper portion of Fig. 1, the space between them will be slightly wedge-shaped or tapered to 90 toward the side of the block. At the inner ends of the inclined portions 17 are the shoulders 18, and between the shoulders is a straight portion 19, the two straight portions 15 and 19 being so arranged that when 95 one block is placed upon another similar one, these straight portions will be adjacent to each other.

The reference numeral 20 indicates a binding wire or rod of the kind ordinarily em- 100

ployed in structures of this kind, and 21 indicates the mortar or cement placed between two adjacent rows of building blocks.

In practical use, my improved building blocks are laid to form a wall in the manner shown in the accompanying drawings. After the first layer is placed in position, and assuming that the structure is a circular building such as a silo, the operator lays 10 a binding wire or rod on top of the circular layer of building blocks. In this connection, it is to be understood that the kind of binding wire or rod usually employed for structures of this kind is made of relatively 15 soft metal which can be comparatively easily bent. Frequently in handling and applying these binding wires or rods, the material becomes bent or kinked in such a manner that it is difficult and impracticable 20 to again make it perfectly straight. Hence, the binding wire or rod will not at all points around the circumference of the wall lie flat against the straight portion 15, as shown in Fig. 1, but there must be a space between 25 two adjacent building blocks of, say, for instance, an inch in which this wire or rod is placed, although the wire or rod of itself may be less than one quarter of an inch in thickness.

30 Obviously, if the two adjacent building blocks had flat adjacent surfaces, the layer of mortar would have to be substantially an inch thick, in order to provide for the kinks or bends in the wire or rod just described.

35 It has been found undesirable to have a layer of mortar or cement of approximately an inch in thickness because of the large surfaces of cement or mortar exposed to the weather which is greatly cut away by the 40 action of the elements. By my improved construction, there is ample room left to accommodate such bends or kinks in the binding wires or rods, and at the same time, after the wall is laid, the part of the cement or 45 mortar exposed to the weather is relatively small.

Another very material advantage in my improved construction is that the portion of 50 mortar or cement between the wire or rod and the inner surface of the wall is wedge-shaped or tapered. When a heavy pressure is applied to the inner surface of the wall at one point, there is, of course, a tendency for the wire to pull the cement or mortar from 55 between the layers of blocks. By having this portion of the cement or mortar made wedge-shaped with annular ribs, instead of the wire pulling the cement or mortar from between the layers of blocks, it must crush 60 this wedge-shaped portion, and inasmuch as the strength of cement or mortar is much greater in resisting crushing strains than it is in resisting adhesion or shearing strains, the strength of the wall is thereby greatly 65 increased in comparison with a wall built up

with layers of cement or mortar of substantially uniform thickness throughout.

Another advantageous feature is by having the square shoulders 14 and 18, the wedge-shaped layer of mortar is firmly held in position even though it should become broken loose from both of the adjacent building blocks. I am aware that heretofore building blocks of this class have been provided with longitudinal grooves on their 70 adjacent surfaces, and I do not desire to be understood as claiming broadly the idea of providing such grooves.

Another advantageous feature of my invention is that by having the adjacent edges 80 of the building blocks tapered or inclined in the manner shown, the blocks will have a tendency to center themselves as a pressure is applied to them when laid in position, thus making it comparatively easy for the 85 operator to lay up a wall with the sides of the blocks perfectly in a line with each other.

It is obvious that substantially all of the 90 advantages of my invention can be obtained by placing the blocks in positions inverted relative to the positions illustrated in the drawings, and I therefore do not desire to be understood as limiting my invention to the use of the blocks in the manner illustrated 95 in the drawings.

I claim as my invention:

1. An improved building block having on its top surface a central, longitudinal groove, upright shoulders at the sides of the groove 100 and inclined surfaces extending from the said shoulders outwardly and upwardly to the sides of the building block, having on its under surface a central, longitudinal groove with downwardly extended shoulders at the sides thereof and with inclined surfaces from said shoulders to the sides of the block extended outwardly and upwardly, said inclined surfaces being at such relative angles that when two adjacent similar blocks 110 are placed together, one above the other, there will be between them a space to receive mortar, which space will be thickest at its central portion and tapered toward both sides for the purposes stated.

2. An improved article of manufacture comprising a building block of vitrified clay, comprising two upright side walls, a central horizontal partition, a top member having a longitudinal groove at its center, upright shoulders at the sides of the longitudinal groove and inclined surfaces extending from said shoulders to the sides of the building block and being inclined upwardly and outwardly, the bottom member being provided on its under surface with a central, longitudinal groove with downwardly extended shoulders at its sides and with inclined portions extending from said shoulders to the sides of the block and inclined upwardly 120 125 130

and outwardly, the latter inclination being arranged closer to a line at right angles to the sides of the block than the inclination of the corresponding surfaces at the top of

5 the block, for the purposes stated.

3. An improved building block, having longitudinal openings through it and one of its longitudinal edges concaved and the other convexed, and said edges being provided with a central longitudinal groove

having shoulders parallel with the longitudinal sides of said block, the concaved edge being of less curvature than the convexed edge.

Des Moines, Iowa, Sept. 27, 1912.

HALVER R. STRAIGHT.
